MAX SCHÄFER, OF STUTTGART, GERMANY, ASSIGNOR TO THE FIRM OF ROBERT BOSCH, OF STUTTGART, GERMANY.

INTERRUPTER FOR ELECTRIC IGNITION-MACHINES.

1,104,007.

Specification of Letters Patent.

Patented July 21, 1914.

Application filed February 8, 1912. Serial No. 676,473.

To all whom it may concern:

Be it known that I, MAX SCHÄFER, a subject of the Emperor of Germany, residing at 107 Aeussere Büchsenstrasse, Stuttgart, Germany, have invented certain new and useful Improvements in Interrupters for Electric Ignition-Machines; and I do hereby declare the following to be a full, clear, and exact description of the invention, such as will enable others skilled in the art to which it appertains to make and use the same.

This invention relates to interrupters for electric ignition machines for the ignition of combustible gases in internal combustion engines, and is particularly directed to mechanism which permits the adjustment of the period of ignition, said mechanism forming a part of the casing for the interrupter and being connected to a stationary part of the casing so that it is reliably held therein in any position to which it may be turned to advance or retard the spark and also so that it may be easily removed therefrom for inspection or repair of the interrupter parts. Interrupters of this kind are usually located on the prolongation of the armature shaft of the electric ignition machine and they sometimes have a rotatable lever provided with a platinum contact which is normally held by a spring in engagement with another rotatable contact. These interrupter parts are generally incased and during operation they coöperate with actuating cams for periodically separating the contacts to interrupt the electric ignition circuit. In order to adjust the period of ignition with interrupters heretofore customary, the actuating cams were carried by a cam-ring adapted to be turned independently of the casing to a position corresponding to the adjustment desired.

It is essential in all forms of interrupters that the parts incased should be readily accessible without the use of special tools for inspection and repair and that the adjustable part should turn easily during the period of adjustment but should be reliably held in any adjusted position. The present invention contemplates forms of construction which fulfil all of these requirements by employing a casing for the interrupter comprising a stationary part with a peripheral offset in the form of a groove or a ledge, an adjustable part having a coöoperating offset and a spring fitting the offsets to hold the

two casing parts together in any position to which the adjustable part may be turned. Furthermore, the spring is deformable and of such form and so arranged that the adjustable part of the casing may be withdrawn axially from the stationary part at any position of adjustment in order to expose the interrupter parts.

In the accompanying drawings illustrating several modifications of my invention, Figure 1 is a longitudinal section on line 1—1 of Fig. 3 through an interrupter; Fig. 2 is a section on line 2—2 of Fig. 1, also showing in outline a magneto to which the invention may be readily applied; Fig. 3 is an elevation of the interrupter with the cover of the casing removed; Fig. 4 is a section on line 4—4 of Fig. 5 of a modified form of construction within the invention, with the interrupter parts omitted; Fig. 5 is a section on line 5—5 of Fig. 4, showing the casing combined with a magneto; Fig. 6 is an elevation, in half section, of another modification within my invention; Fig. 7 is an elevation of the casing of Fig. 6, applied to a magneto; Fig. 8 is an elevation, partly in section, on line 8—8 of Fig. 9, of another modification within my invention; Fig. 9 is a section on line 9—9 of Fig. 8 of the casing combined with a magneto; Fig. 10 is a longitudinal section showing another form of construction for holding the stationary and adjustable casing parts together; and Fig. 11 is a section on line 11—11 of Fig. 10, particularly showing the expansion spring.

In the drawings, the adjustable casing part is indicated by *a* and the stationary casing part connected thereto is indicated by *b*. Upon the inner periphery of *a* are located the actuating cams 22, two being shown as an example in this case.

The interrupter shown in detail in Figs. 1 and 2 does not form any part of this invention and is illustrated merely to indicate the practical application thereof.

Upon a disk 13 fastened to the armature shaft 12 is screwed an insulated metal block 14 which carries one of the interrupted contacts 15. The coöperating contact 16 is mounted at the end of a bent lever 17 which can rock upon a pin that is covered in Fig. 3 by a spring 18. The lever 17 carries a block of fibre 19 and a bow-shaped leaf spring 20, one end of which is attached at 21 to the disk 13, and holds the lever 17 in such posi-

tion that the contacts 15 and 16 are normally pressed into engagement with each other. The actuating cams 22 project into the path of the fiber block 19, and when the shaft 12 is rotated the fiber block 19 periodically engages them so that the lever 17 is rocked against the stress of the spring 20, thereby separating the two contacts 15 and 16 and interrupting the electric circuit of the magnet 23. If the adjustable casing part *a* is turned relatively to the stationary casing part *b*, the period of interruption and therefore the period of ignition may be adjusted to any desired advanced or retarded position within the range of adjustment.

In Figs. 1 to 3, the projecting rim of the stationary casing part *b* encompasses the edge of the adjustable casing part *a*, and the peripheral offsets in the form of registering grooves are cut in the opposite surfaces of these parts. The split spring *d* is bowed outwardly at *c*, Fig. 2, and projects into the peripheral recess of the stationary casing part *b*, whereby the spring is prevented from turning when the adjustable casing part *a* is turned by the adjusting rod fastened to *c*. The spring *d* has its section so arched that it projects also into the groove of the adjustable casing part *a* and in this manner holds the two parts together in any position to which the adjustable part is turned. Furthermore, as a result of the fact that the spring *d* may be slightly deformed the adjustable casing part may be withdrawn axially from the stationary part of any position of adjustment, simply by pulling on it with sufficient force to disengage the two parts.

In the modification shown in Figs. 4 and 5, the peripheral grooves for the spring *d* are on the inner surface of the adjustable casing part *a* and the outer surface of the stationary casing part *b*. The spring *d* is split at one place and engages on the two sides of the lug *c*, which projects within the groove on the stationary casing part, so that the spring cannot turn when the adjustable casing part is being turned.

In the modification shown in Figs. 6 and 7, the previously described peripheral grooves on the casing parts are replaced by the ledges *e* and *f*, which are so constructed that the casing parts fit along their flat surfaces. Both of these ledges are encompassed and held together by an annular spring bent in cross section into the form of a cup or trough. As in Figs. 4 and 5, the spring *d* of this modification is split and abuts against the lug *c* on the stationary casing part *b*, so that the spring cannot turn when the adjustable casing part *a* is turned.

The modification shown in Figs. 8 and 9 differs from Figs. 1 to 3 in that a helical spring *d* is used instead of a flat spring. In

order to hold the helical spring *d* in one of the casing parts, for instance the adjustable part *a*, there may be inserted within the spring, a smooth split wire ring which is under sufficient stress to hold the helical spring in the groove of the adjustable part, when the adjustable part is being withdrawn.

In Figs. 10 and 11, the locking mechanism consists of two parts, a split ring *d* and a bowed leaf spring *g* of polygonal form, likewise split at one place. In the position shown in the drawing, the straight line parts of spring *g* crowd the ring *d* inwardly. If the adjustable casing part *a* is placed within the stationary casing part *b*, the straight line parts of spring *g* yield and are forced into the peripheral groove on the inner surface of the stationary casing part. However, as soon as the peripheral groove on the outer surface of the adjustable casing part *a* comes opposite the ring *d*, the ring is pressed by the spring *g* into the groove and thereby locks the two casing parts together in any position to which the adjustable part may be turned. The adjustable casing part *a* may be withdrawn axially from the stationary casing part *b* at any position of adjustment simply by pulling it out as in all the other forms of construction.

Having thus described my invention what I claim is:

1. In combination with an interrupter for an electric ignition machine, a casing for the interrupter comprising a stationary part, an adjustable part, and a deformable spring frictionally engaging both of said parts to hold them together in any position to which the adjustable part may be turned.

2. In combination with an interrupter for electric ignition machines, a quickly detachable casing for the interrupter comprising a stationary part, an adjustable part, and locking mechanism frictionally engaging both of said parts at any position to which the adjustable part may be positioned, said locking mechanism being disengageable by pulling the adjustable part axially.

3. In combination with an interrupter for an electric ignition machine, a casing for the interrupter comprising a stationary part provided with a peripheral offset, an adjustable part provided with a peripheral offset and carrying an actuating cam for the interrupter contacts, and a spring fitting said peripheral offsets to hold the two parts together at any position to which the adjustable part may be turned.

4. In combination with an interrupter for an electric ignition machine, a casing for the interrupter comprising a stationary part provided with a peripheral offset, an adjustable part provided with a peripheral offset and carrying an actuating cam for the

interrupter contacts, and a deformable spring fitting said peripheral offsets to disengageably hold the two parts together at any position to which the adjustable part 5 may be turned.

5. In combination with an interrupter for an electric ignition machine, a casing for the interrupter comprising a stationary part provided with a peripheral offset, an adjustable part provided with a peripheral offset and carrying an actuating cam for the interrupter contacts, a lug extending within the peripheral offsets of one of said parts, and a split spring fitting said peripheral 10 offsets and abutting against said lug to hold the two parts together at any position to which the adjustable part may be turned.
- 15 6. In combination with an interrupter for

an electric ignition machine, a casing for the interrupter comprising a stationary part 20 provided with an exterior peripheral ledge, an adjustable part provided with an exterior peripheral ledge and carrying an actuating cam for the interrupter contacts, a lug on one of said parts, and a deformable split 25 spring encompassing said ledges and abutting said lug to disengageably hold the two parts together at any position to which the adjustable part may be turned.

In testimony whereof I affix my signature, 30 in presence of two witnesses.

MAX SCHÄFER.
